DEICER BOOT APPLYING TOOL

Raymond F. Martin, Fairborn, Ohio

Application June 15, 1951, Serial No. 231,888

4 Claims. (Cl. 254—77)

(Granted under Title 35, U. S. Code (1952),
sec. 266)

1

The invention described herein may be manufactured and used by or for the Government for governmental purposes without payment to me of any royalty thereon.

This invention relates to a tool for applying rubber de-icing boots to the leading edges of aircraft wings, elevators and the like.

At present, the application or replacement of de-icer boots requires considerable time and labor. The edges of the de-icer boots must be drawn under retainer strips and holes in the edges of the boots must be aligned with holes in the retainer strip so that each pair of holes may be held together by the insertion of one screw. The method heretofore in use required one man to stand on the wing top surface and pull rearwardly on string loops by pulling one or two at a time while another man stood in front of the wing to align the holes in the de-icer boot edge with the holes in the retainer strip and then to insert the screws through both holes and the threaded apertures in the wings. This operation was also somewhat dangerous, since a considerable pull was required to draw the edges of the boot up to place under the retainer strip. When, as sometimes happened, the string loops broke, the man on the wing often lost his balance and tumbled or slid off the wing, possibly sustaining injury from the fall.

Among the objects of the invention therefore is the provision of a tool, by the use of which one man who, while standing on a support in front of the wing can quickly and efficiently draw the edge of the boot into place, align the screw openings of the de-icer boot and the retaining strip and place the screws with the minimum amount of effort in the minimum amount of time. The tool draws a portion of the length of the boot edge at each operation to clamping position and holds it securely in such position without attention from the operator, while he inserts the screws.

Briefly stated, the device is a manually operable device for applying a de-icing boot to the leading edge of an airplane wing and comprises anchoring means for creating frictional or other resistances to drag without perforation of the wing, between the anchoring means and the unperforated top surface of the wing. Levers are used for shortening the distance between the anchoring means and the upper edge of the boot to be applied. Fulcrum means are provided for the pivoted attachment of the lever means and equalizing or distributing means are provided between the fulcrum means and the top edge of the boot for distributing the tension created by the oper-

2

ation of the compound lever. Attaching means, which may be hooks, are provided for connecting the distributing means to the boot edge through looped cords.

Referring now to the accompanying drawings: Fig. 1 is a semi-plan view taken from an angle from a position above the aircraft wing and the tool;

Fig. 2 is a somewhat diagrammatical side elevation of the tool showing two positions of the compound lever together with the resulting stretch; and

Fig. 3 is a cross section of the fulcrum means or the supporting plate base, the view being taken 15 along the line 3—3 of Fig. 1.

Referring again to Fig. 1, 10 is an engine housing or pod of an airplane and 11 is a portion of an aircraft wing connected thereto through an angled stringer 11a. 12 is the leading edge of 20 the wing 11 and 13 is a rubber de-icing boot connected thereto. 14 is the upper edge or hem of the boot 13, this edge being provided with a plurality of evenly spaced screw holes at 15. Through alternate screw holes 15, cord loops 16 are provided, which are substantially of equal length that appear to be of unequal length in the drawing on account of the various factors such as slack and stretch.

The tool which is the subject of my invention 30 comprises a container 17 which may be filled from one side of one end with weights, which may be bags of lead shot so that it will weigh from 175 to 200 pounds. This container when so filled is known as a skid weight or an anchor. It is provided on its bottom with a rubber or felt surface 17a so as to exert a large amount of friction in conjunction with a dry wing surface. The shape of the container preferred is that of a truncated pyramid or half pyramid, but the shape is subject 35 to considerable choice. At its forward edge, the container 17 is provided with a flange 18 to which its supporting plate or base 19 is connected by flexible cords or cables 20 which are preferably attached to the weight and the plate or base by 40 means of clevises.

The supporting plate or base has a shape which 45 is generally that of a long narrow rectangle and is provided with ears or flanges at its ends. It also has an extension stabilizer 22 which extends 50 forwardly from the base or plate at a point approximating a middle of the longer side of the rectangle. Between the ears or flanges there is mounted a fulcrum bar 21 about which is fitted a shorter fulcrum sleeve 23, which is also shown 55 in Fig. 3. The supporting plate 19, like the weight

is fitted with a rubber or felt bottom, this bottom falls upon 19a extending over to the full length of the extension stabilizer 22.

To the fulcrum sleeve 23 there is attached preferably by welding a separate lever 24 which has the form of a flat bar. To it is hingedly attached a push rod 25 which has a handle 26 for manual operation. An upper hinge 27 accommodates the push rod 25. A few inches above the junction between the operating lever 24 and the fulcrum sleeve 23 there is a hinge 28, the upper part of which is elongated and is attached at its outer end to a distributing or equalizing plate 29 which also has the form of a narrow rectangle. The plate 29, which is also known as a pull plate, is perforated at equally spaced intervals for the accommodation of a ring 30 by means of a clevis 31. There is a turn buckle 32 which, on its outer end bears a hook 33 in which is retained a cord loop 16 which connects each hook with the de-icer hem 14. It is now evident that if the cord and turn buckles are short enough so that in their unstretched position that causes the operating lever 24 to take the angular position shown, a powerful leverage can be exerted by a manual push on the handle 26 to cause the compound lever 24-25-27-28 to pull the de-icer edge 14 toward the weight or anchor 17. This action is illustrated in Fig. 2 in which the full lines showing of the lever system indicates the original position and the dashed line showing indicates a subsequent position. When the final position of the lever system is such that both rods 24 and 25 are horizontal, the tool is locked and a pull through the elements 16-33-32-30-29-28 will not be able to pull the levers to their former series of positions. The position of the anchor 17 should be chosen in relation to the wing so that when the lever system is folded down parallel with the wing surface, the holes 15 in the de-icer edge or hem will coincide with holes 34 either directly in the wing or in a strip element attached thereto. In the position of such registry, a retainer strip is placed over the hem and over the holes 34 so that holes 36 in the retainer strip coincide with the holes 15 and 34. Screws are then manually placed to extend through all three holes and are not tightened until the cord loops 16 are removed or cut and other holes 15 further on or further toward the housing 10 are provided with cords for a subsequent levering operation.

In the preferred form of the invention which is shown in the drawings, the purpose of the sleeve 23 is to make possible two or more levering operations before it becomes necessary to move the weight container 17 to a new position on the wing. The sleeve 23 is materially shorter than the bar 21 about which it fits so that it can be moved to approximately three positions on the bar 21 without overlapping previously occupied space. In each of the new positions, a new set of holes 14 can be worked upon and a corresponding additional length of edge or hem 14 tightened down and secured. New cords or loops 16a are shown positioned for the next levering operation. Alternatively, for subsequent levering operation, the position of the tool may be changed by moving the weight 17 and the supporting plate 19 a corresponding distance toward the engine housing 10. For such operation, the sleeve 23 may be omitted entirely.

It will be evident to skilled airplane mechanics that certain changes may be made in the construction of the tool without departing from the spirit of the invention. For example, the weights

17 may be made solid instead of as a container to be filled with other weights. Suction cups are the patentable equivalents of weights. The fulcrum bar 21 may be made to turn directly in the supporting plate or base flanges instead of the sleeve being provided to turn about the bar; and other connecting means besides hooks and clevis may be provided to connect the cords 16 and the pull plate 29.

Another feature of value which nevertheless may be dispensed with is, such a weight 24a which is attached to the top of operating lever 24. The function of this weight is to hold the bar 24 off vertical and over toward the weight 17 for operating convenience, since then it will not fall down on the wing surface.

After one set of holes 15-35-34 has been provided with screws, its alternate neighbors are also provided with screws as the operation progresses in the direction of the engine housing. Some mechanics use temporary pins before placing the screws. It is immaterial whether the work is begun near the engine housing or near the wing tip.

What I claim is:

1. In a device for applying a de-icing boot to the leading edge of an airplane wing, a skid weight provided with a means to frictionally grip on the unperforated top surface of the wing, a supporting plate, flexible connectors joining the weight and plate, the supporting plate having a fulcrum bar substantially coextensive with the plate and a forwardly extending stabilizing extension for said plate, a fulcrum sleeve substantially surrounding said fulcrum bar, said sleeve being laterally slidable and substantially rotatable thereon, an operating lever attached to said fulcrum sleeve, a push rod hingedly attached to the outer end of said operating lever, a pull plate hingedly attached to the lower part of said operating lever, a plurality of evenly spaced rings attached to said pull plate, a turnbuckle pivotably attached to each ring substantially by its inner end and a hook at the outer end of each turnbuckle whereby a plurality of strings attached to the upper edge of a de-icing boot may be evenly pulled to bring into register a plurality of screw-receiving holes in said edge simultaneously with an equal number of like holes in a strip closely attached to said wing.

2. A device according to claim 1 in which the hinges connecting pull plate and operating lever and the push rod and the operating lever have sufficient degrees of freedom so that the compound lever formed by connecting the operating lever and push rod may be folded down substantially parallel to the pull plate top surface to resist a pull applied to the pull plate, and a weight attached substantially at the outer end of the operating lever, said weight being positioned to incline the operating lever normally toward the skid weight.

3. A device according to claim 1 in which the fulcrum sleeve is materially shorter than the fulcrum bar whereby shifting said sleeve on said bar makes it possible to pull several successive lengths of the upper edge of the de-icer boot into screw hole registry without changing the position on the wing surface of either the skid weight or the supporting plate.

4. A portable manually operable device for applying a de-icing boot to the leading edge of an airplane wing, comprising, anchoring means having a lower frictional surface for frictional supporting engagement with the upper surface of

the wing to create resistance to drag between the anchoring means and the top surface of the wing, a lever arm pivotally and slidably connected to the anchoring means for swing movements toward and away from the leading edge of the wing and transverse sliding adjustment movements, means pivotally connected to said lever arm intermediate the pivotal and slidable connection aforesaid and its free end including a plurality of spaced connectors adapted to be connected to the upper edge of the de-icer boot at spaced points, and individual length adjusting means in each of said spaced connectors.
